UNITED STATES PATENT OFFICE.

RUDOLPH G. DRESSLER, OF CONEY ISLAND, NEW YORK.

FLYING-MACHINE.

No. 919,834.

Specification of Letters Patent. Patented April 27, 1909.

Application filed July 1, 1908. Serial No. 441,334.

To all whom it may concern:

Be it known that I, RUDOLPH G. DRESSLER, a citizen of the United States, residing at Coney Island, in the county of Kings and 5 State of New York, have invented certain new and useful Improvements in Flying-Machines, of which the following is a specification.

This invention relates to improvements in flying machines of that type which are intended to be operated by one person who operates both the propelling and steering devices; and for this purpose the invention consists of a flying machine comprising an 10 upright supporting frame, an aeroplane supported at the upper part of the frame, oscillating wings hinged to the frame below the aeroplane and extending at both sides of the same, said wings being provided with 15 movable blades that swing above the wings during the downward motion and below the wings during the upward motion of the same, lever mechanism for imparting oscillating motion to the wings, a steering rudder 20 located at the lower front-part of the frame, and mechanism for setting the rudder into the required position.

The invention consists further of certain 25 details of construction which will be fully described hereinafter and finally pointed out in the claims.

In the accompanying drawings, Figure 1 represents a perspective view of my improved flying machine shown in position for 30 starting it, Fig. 2 is a front-view of the same, drawn on a smaller scale, and Figs. 3 and 4 are perspective views of the blades on the outer ends of the wings, showing them in position respectively at the commencement of the downward and upward 35 strokes.

Similar letters of reference indicate corresponding parts.

Referring to the drawings, *a* represents 40 an upright frame which is provided with a platform *a*¹ at the lower end, said platform having rollers *a*² at the under-side for moving it over the ground. The upright frame *a* is composed of two pairs of inclined and 45 intersecting front- and rear- rods *a*³ which are stiffened by suitable braces *a*⁴ that are arranged at the top and bottom of the frame. The upper end of the frame is suspended by thin steel wire ropes *a*⁵ which are connected 50 at their upper ends by a short shaft *b* carrying a roller *b*¹ so as to permit the frame to

be suspended from a horizontal rail *r*, which is slightly curved in downward direction at the outer end, as shown in Fig. 1. The roller *b*¹ passes over the rail *r* when the flying machine is to be started. The person who desires to use the flying machine takes his stand on the platform *a*¹ when he desires to work the machine with his arms or feet.

On the upper part of the supporting frame *a* at the point where the upper ends of the intersecting rods are connected by the brace-rods *a*⁴, is arranged an aeroplane *d* which is supported at an oblique angle of inclination to the horizontal plane and formed of transverse convexo-concave sections constructed of a frame of thin steel or other tubes that are connected by oiled silk and canvas or other suitable waterproof material. Below the aeroplane *d* are arranged two curved 70 wings *w* which are hinged at their inner ends to the supporting frame at the point of intersection of the front- and rear- rods *a*³. The wings *w* are made considerably larger than the aeroplane, of light ribs of ratan, 75 steel or other material, and covered by oiled silk, canvas or other waterproof fabric. The wings *w* are operated by levers *l* that are pivoted to the under-side of the wings and connected with a combined handle-and-foot 80 rod *l*¹ which is moved up and down by the hands or feet of the person using the machine so as to impart oscillating motion to the wings.

At the outer ends of the curved wings *w* 85 are arranged a series of movable blades *f*, which are made of a light frame and oiled silk webbing and hinged at one side to the ribs of the wings, while the opposite sides of the blades are connected by thin yielding 90 wire or other strings *f*¹ with the ends of the adjacent ribs, so that during the upward motion of the wings the blades are moved in downward position and held at a suitable angle of inclination below the wings, as 95 shown in Fig. 4, while when the wings are moved in downward direction the blades assume a position above the wings at a suitable angle of inclination to the same.

When the machine is placed against the 100 wind and the operator moves the raised wings from their highest point downward by means of the lever-connections, he places his shoulders against two shoulder-rests *h* so as to obtain more strength for the first few 105 ascending strokes. The shoulder-rests *h* are connected by curved rods *h*¹ with the sup-

porting frame at the points of intersection of the front- and rear- rods. The wings will then assume a partly concave and partly convex position and the movable blades, being held in position by the wire strings, will rise to about an angle of 25° , giving thereby forward propulsion to the machine, while at the same time the wings lift the structure off the ground. At the same time as the forward motion is imparted, the aeroplane, which is located above the wings, assists, owing to its angle of inclination, in lifting the machine off the ground and prevents it from descending during the next upward stroke of the wings. The movable blades drop down during the up-stroke of the wings into a corresponding angle to the wings, but below the same, and assist thereby the forward propulsion, the wings assuming then a convexo-concave position, as shown by the lower dotted lines in Fig. 2, which prevents the machine, in conjunction with the aeroplane, from being moved in downward direction, as shown.

25 In front of the frame *a* is arranged a steering rudder *r*¹ which is pivoted to an upright rod *r*² that is connected with a horizontal rod *r*³ which is attached to the platform *a*, the inner ends of the rudder being connected by suitable ropes *r*⁴ passing over pulleys *r*⁵ with the lower part of the frame so as to be readily operated by the hands of the person using the flying machine. By pulling the rope *r*⁴ at one side the rudder is moved in one direction and by pulling the opposite rope *r*⁴ the rudder is moved in the other direction, so as to steer the flying machine thereby. As the weight of the operator is in the center of gravity of the entire structure, a perfect equilibrium is obtained, so that even when the wings are not operated, the person operating the flying machine and the structure itself are enabled to soar in the air like a parachute so as to permit the gradual descent of the flying machine, even if some of the wings should become injured or broken, the structure acting then in the nature of a life-saving apparatus.

50 Instead of operating the lever mechanism by the hand or foot, a small motor may be used for actuating the same, which would then leave the hands free for operating the starting of the motor and the steering rudder.

55 The movement of the wings in connection with the opening and closing of the blades during the upward and downward motion of the wings, produces the forward propulsion, lifting and soaring of the machine in an effective and reliable manner, forming there-

by a flying machine of small size and cost, which can be operated with absolute safety, with or without power, in flying, soaring, ascending and descending.

Having thus described my invention, I claim as new and desire to secure by Letters Patent:

1. A flying machine comprising an upright supporting frame having a platform at the lower end, an inclined aeroplane at the upper end, oscillating wings below said aeroplane, and movable blades on the wings adapted to move up and down with the downward and upward motion of the wings. 70

2. A flying machine comprising an upright supporting frame, an inclined aeroplane at the upper end of the same, oscillating wings below said aeroplane, means for oscillating said wings, and movable blades at the outer ends of the wings adapted to swing down 75 and up during the upward and downward motion of the wings. 80

3. A flying machine comprising an upright supporting frame, an inclined aeroplane at the upper end of the same, oscillating wings below said aeroplane, means for oscillating said wings, movable blades on the wings adapted to swing down and up during the upward and downward motion of the wings, a steering rudder supported at the front- 85 part of the frame, and means for operating the same. 90

4. A flying machine comprising an upright supporting frame provided with a platform at the lower end, an inclined aeroplane stationary on the upper end of the frame, said aeroplane being curved in transverse direction, oscillating wings below said aeroplane provided with movable blades on said wings, means for actuating said wings, a steering rudder located below the wings, and means for operating the same from the supporting frame. 95 100

5. A flying machine comprising an upright supporting frame, a fixed inclined aeroplane at the upper part of the frame, and oscillating wings hinged to the frame below the aeroplane and provided with flexible ribs and movable blades between the ribs, said wings assuming a partly concave and partly convex shape during the down-stroke and a convexo-concave shape during the up-stroke. 110

In testimony, that I claim the foregoing as my invention, I have signed my name in presence of two subscribing witnesses.

RUDOLPH G. DRESSLER.
